UNITED STATES PATENT OFFICE.

ROSS VAUGHAN, OF NEW YORK, N. Y., ASSIGNOR TO AMERICAN CAN COMPANY, OF NEW YORK, N. Y., A CORPORATION OF NEW JERSEY.

SPOUT FOR RECEPTACLES.

1,224,583.

Specification of Letters Patent.

Patented May 1, 1917.

Application filed April 21, 1914. Serial No. 823,341.

To all whom it may concern:

Be it known that I, Ross VAUGHAN, a citizen of the United States, residing at New York, in the county and State of New York, have invented a new and useful Spout for Receptacles, of which the following is a specification.

This invention relates to spouts for receptacles used to hold sugar, salt, or any material that can be discharged through a comparatively small opening; and the object of my invention is to provide a spout that can be easily secured in position after the receptacle is filled and that in a cheap and efficient manner.

This invention is designed as an improvement on that shown in my application filed October 30, 1913, Serial Number 798,186; and the object of the present invention is to eliminate the flexible material used in forming the hinged connection, and in substituting therefor integral lugs so positioned that by bending them under the receptacle walls the spout will be held in position so that it will pivotally turn on a supporting part of the receptacle casing.

As the present invention is designed as an improvement on my aforesaid invention I have shown the spout as it would be connected with a metal container, or receptacle having a cover in which the spout is mounted; but it will be understood that while this method of securing the spout in the opening is very desirable when the sides of the spout are made divergent owing to the stress placed on the hinged connection in opening and closing, the usefulness of the special form of hinging is not limited to a spout with flaring sides.

My invention is illustrated in the accompanying drawing, in which—

Figure 1, is a top plan view of a receptacle, with my invention applied thereto.

Fig. 2, is a plan of the blank which I may use to form my improved spout;

Fig. 3, is a vertical section of a cover of the receptacle, on the line 3—3 of Fig. 1, with the spout in full lines;

Fig. 4, is a bottom plan view of the cover with the spout in place; and

Fig. 5, is an elevation of the top of a receptacle with the spout open.

In the drawing like numerals of reference refer to the same parts in each of the views.

In practice I provide a spout 6, formed from a blank 7, which is bent on the dotted lines to form a substantially rectangular top 8, and two sector sides 9, with the curved edges 10 equidistant from the points 11, at the connection between the respective sides 12 and the top whereby the dotted lines in Fig. 2, are respectively radii of the sector sides so that when the spout is mounted in an opening 13, in the receptacle the curved edges 10, of the sides will always be in engagement with the front wall of the opening in any position since the opening is equal in length to a radius of either side.

Each side 9, is provided with a straight side 12, each provided with a projecting tongue, or lug 14, spaced from the top 8, a distance substantially equal to the thickness of the material forming the top 15, of the receptacle, or the thickness of any wall of the receptacle in which the opening 13, is formed; and the opening 13, is provided at the rear end with an inwardly-projecting wall whereby a ledge 16, is formed, intermediate of the sides of the opening, adapted to support the rear end of the top 8, which is pivotally held thereon by turning the lugs 14, outwardly underneath the inner wall of the receptacle adjacent to the opening after the spout is placed in position, which can be easily done with an instrument inserted through the opening 13, as the lugs 14, are limited in width, being less than half the length of the side 12, of which each is a part. By providing a stop 17, at the ends of the sector sides where the curved edges 10, connect with the straight sides 12, the spout can not be turned out of the opening 13, after the lugs 14, are turned in under the receptacle wall. I also provide the top 8, with an extension 18, adapted to overlap a portion 19, of the receptacle at the front of

the opening 13, whereby both the front and rear ends of the spout are supported by the receptacle wall when the spout is closed and the rear end is supported when the spout 5 is being opened and closed.

In operation the hole 13, is punched in the receptacle casing at any time prior to the insertion of the spout, preferably during the formation of the receptacle. The 10 spout is inserted by putting it in the position illustrated in Fig. 5, first catching the stops 17, under the wall of the casing at the front of the opening, and then pressing the spout down until the rear edge of the top 15 rests on the ledge, or projection 16, when the tongues, or lugs 14, will have entered the opening 13, and can be turned in under the adjacent walls of the casing. As these lugs are spaced from the top 8, of the spout 20 a distance substantially equal to the thickness of the receptacle casing in which the hole, or perforation 13, is formed, when the spout is in a closed position the edges of the two lugs will be presented to the under wall 25 of the receptacle casing, and will firmly hold the rear of the spout on the ledge, or projection 16, while when the spout is open these lugs will still hold the spout firmly on the ledge owing to the fact that they are 30 turned in under the receptacle casing. In any intermediate position of the spout the lugs will hold the spout in place on the ledge while permitting the turning of the rear edge of the spout on this ledge whereby 35 the spout is pivotally mounted on said ledge, and can be freely opened and closed with the ledge as the pivotal support.

As the lugs are an integral part of the sides of the spout they are formed at the 40 same time the blank shown in Fig. 2, is stamped out of the sheet metal; and as the front walls of the top and sides are curved, it is evident that these lugs can be taken out of a part of the sheet material that would 45 otherwise be left in the scrap so that they are formed without material cost. The spout is easy to make, and easily inserted. It is also effective in use as the contents of the package, or receptacle is discharged 50 through the spout; and the spout can be kept closed at all times when it is not desired to discharge any of the contents. Thus the spout will enable anyone to use 55 the goods contained in the receptacle in a perfectly sanitary manner since they need not be discharged from the receptacle until discharged for the purpose of using, and even then the contents can be discharged without having to be touched with the 60 hands.

In Figs. 1, 3, and 4, I have shown the sides 9, as being divergent, in the same manner as shown in my application referred to above; but this need not be done except

where the spout is to be used on a receptacle 65 having a metal casing, or the part in which the spout is mounted made of metal. If the receptacle has a casing made of pasteboard, and the spout is accurately fitting within the opening 13, the spout will be held in a 70 closed position by friction, as will be understood without having to make the sides divergent. With a metal casing the divergent walls make the spout much more effective 75 in keeping the spout closed, and especially so when shipping.

The construction and operation of the spout is in all respects the same whether mounted in a metal casing, or pasteboard except the making the sides divergent. The 80 lugs 14, are formed in the same way and are turned under the casing wall in the same way to pivotally hold the rear end of the spout top on the ledge 16.

I claim:

1. The combination with a receptacle having an opening in the wall thereof with a portion of the wall projecting inwardly to form a ledge, of a spout pivotally mounted in said opening on said ledge, said spout having a top of a size to cover said opening and ledge and having pendent sides at substantially right angles to said top, each of said sides having a lug spaced from the top 95 a distance substantially equal to the thickness of the receptacle wall, said lugs being proportioned in width to be easily bent after the spout is mounted in said opening.

2. The combination with a receptacle having an opening in the wall thereof with a 100 portion of the wall projecting inwardly to form a ledge, of a spout pivotally mounted in said opening, said spout consisting of a top of a size to cover said opening and ledge, and two sector sides bent at an angle to said 105 top, each of said sides having a lug spaced from said top a distance substantially equal to the thickness of the receptacle wall and of a width less than half the length of one of said sides whereby said lugs may be easily 110 bent with an instrument through said opening with the spout in position.

3. The combination with a receptacle having an opening in the wall thereof with a portion of the wall projecting inwardly on 115 a plane with the surrounding walls of the receptacle to form a ledge, of a spout pivotally mounted in said opening, said spout consisting of a top and two sector sides at an angle to the top, said top having a 120 straight edge adapted to bear on said ledge during the swinging of the spout, and each of said sides having a lug spaced from the top a distance substantially equal to the thickness of the receptacle wall, said lugs 125 being bent at an angle to said sides whereby the top is pivotally held on said ledge.

4. The combination with a receptacle hav-

- ing an opening in the wall thereof with a portion of the wall projecting inwardly to form a ledge, of a spout pivotally mounted in said opening on said ledge, said spout consisting of a top larger than said opening and pendent side wings adapted to enter said opening, each of said side wings having a lug spaced from said top a distance substantially equal to the thickness of the receptacle wall and each lug having a straight edge adjacent to said wall and substantially parallel therewith, said lugs being so positioned and limited in width whereby they may be easily bent by an instrument inserted through said opening, for the purpose set forth.
5. In combination, a container having an opening, a spout pivotally mounted adjacent said opening and comprising a flat central portion adapted to cover said opening and two sides at angles thereto and extending into the opening, one edge of the flat central portion coinciding with the pivotal axis of the spout, and lugs extending at right angles from said sides adjacent the pivotal line of the spout and within the container to hold the spout in proper position with respect to said opening.
6. The combination of a container provided with a dispensing opening formed to provide a tongue extending into said opening and a pouring spout having a central portion with an edge adapted to engage above said tongue and provided with wings 35 extending into said container, each of said wings having lips engaging the inner face of said container behind said tongue and forming with the adjacent edge of said central portion a pivotal connection between 40 said spout and said container.
7. A thin walled container provided with a dispensing opening in one of its walls of substantially rectangular form, one of the sides of said opening projecting into said 45 opening to form a ledge, a pouring spout having a top and side portions; the side portions having arcuate faces and adapted to enter said opening, and the top portion being of larger area than said opening and 50 adapted to rest over and close said opening, one edge of said top portion resting on said ledge, and projections from said side portions resting against the inner surface of the wall of said container adjacent said 55 ledge, and forming with said edge of the top and said ledge a pivotal joint with said container whereby the said spout may be swung from a closed to an open position and remain confined in said opening.

Dated April 20, 1914.

ROSS VAUGHAN.
